(57) **CLAIM**

The ornamental design for a detachable abrasive plate, as shown and described.

DESCRIPTION

FIG. 1 is a front perspective view of an embodiment of a detachable abrasive plate of the present invention;

FIG. 2 is a front side view of the detachable abrasive plate of FIG. 1;

FIG. 3 is a left side view of the abrasive plate of FIG. 1;

FIG. 4 is a right side view of the abrasive plate of FIG. 1;

FIG. 5 is a top side view of the abrasive plate of FIG. 1;

FIG. 6 is a bottom view of the abrasive plate of FIG. 1; and,

FIG. 7 is a back side view of the abrasive plate of FIG. 1.

The broken lines in the drawings represent environmental structure only and form no part of the claimed design.
